CLAIM

The ornamental design for a shoe sole, as shown and described.

DESCRIPTION

1. Shoe sole

1.1 : Perspective

1.2 : Front

1.3 : Back

1.4 : Right

1.5 : Left

1.6 : Top

1.7 : Bottom

The various views of the design show only the right shoe sole; the left shoe sole is not shown as it is symmetrical to the right one.

1 Claim, 7 Drawing Sheets
